ROPE GRIP FOR AERIAL CABLEWAYS

Filed June 28, 1945

3 Sheets-Sheet 3

INVENTORS:
ALBERT FRIEDER.
PAUL ZUBERBUHLER
27 Richardson, David and Norton
ATTYS.

resilient means acting on said jaws to maintain a clamping pressure on the cable, a hanger pivotally mounted at one end to said frame and secured to said load carrier at its other end, a pin mounted for eccentric rotation in said frame to constitute the pivot for one of said jaws, said jaw being loosely pivoted on said pin, and an arm rigidly secured to said pin and articulated to said hanger.

2. A cable gripping mechanism for a cable carrier comprising a frame having parallel slots oppositely disposed, at least two jaws oppositely disposed in said frame, a pin carried in said slots, one of said jaws being carried by said pin, a compression spring located between said mentioned jaw and said frame, said spring acting on said oppositely disposed jaws to maintain a clamping pressure on said cable, a hanger pivotally mounted at one end to said frame and secured to said carrier at its other end, a second pin mounted for eccentric rotation in said frame and carrying the second jaw, and an arm rigidly secured to said second pin and articulated to said hanger.

3. A cable gripping mechanism as claimed in claim 1 comprising a stop located on said frame to limit the movement of said hanger.

4. A cable gripping mechanism as claimed in claim 1 comprising a locking device carried by said frame and cooperating with said jaws to prevent them being opened accidentally.

5. A cable gripping mechanism as claimed in claim 1 comprising a follower extending from said jaw which is carried by said pin mounted for eccentric rotation and an externally disposed cam track to cooperate with said follower whereby said jaws are coupled or uncoupled from said cable.

6. A cable gripping mechanism for a cable carrier comprising gripping jaws for a traction cable, a supporting frame for said gripping jaws, resilient means acting on the jaws whereby the clamping pressure of the jaws on the traction cable may be automatically maintained in spite of variations of the diameter of said cable, a hanger for the carrier to be transported through the agency of said gripping jaws engaging said traction cable, and emergency means mechanically connecting said gripping jaws and said hanger in such a manner that, in the closed position of said gripping jaws engaging said traction cable, the force exerted on said gripping jaws by said resilient means, acting through these gripping jaws and said emergency means on the hanger, maintains said hanger against a stop on said supporting frame against the action of the weight of the carrier to be transported acting on said hanger and tending to move it away from said stop, so that in case of a breakdown of said resilient means, the hanger may move away from said stop under the action of the weight of the carrier to be transported and, acting through said emergency means, thus displace said gripping jaws against a stop to re-establish the gripping pressure of the gripping jaws on the traction cable, said gripping pressure being thus maintained at least partially by the action of the weight of the carrier to be transported acting on the hanger.

7. The combination of cable gripping mechanism as claimed in claim 1, and a stationary safety control mechanism having an extension disposed below said cable, along its path, a distance sufficient to bring said jaws into contact

with said extension when said jaws are open or improperly closed and not gripping said cable, said jaws contacting said extension while tracking said cable during such condition to actuate an alarm or stop the cable drive.

5 8. A cable gripping mechanism for a cable carrier comprising a frame, two gripping jaws carried by said frame, at least one of said jaws being displaceable relative to said frame in a direction toward and away from the other jaw, a pivot pin for said displaceable jaw, said pivot pin being mounted in said frame for displacement in a direction toward and away from said other jaw, said displaceable jaw being swingably mounted on said pivot pin, a hanger for the carrier pivotally mounted in said frame and urged by the load toward a normal position, and means connected with said hanger and acting on said pivot pin to urge it toward said second jaw due to the tendency of said hanger to assume said normal position.

20 9. A cable gripping mechanism for a cable carrier comprising a pair of gripping jaws for a traction cable, a supporting frame for said jaws, resilient means acting on one of said jaws to exert gripping pressure on the cable, a hanger for the carrier to support the load thereon, means connecting said hanger to the other of said jaws to exert gripping pressure on the cable proportional to the weight of the load, and an emergency stop to hold said first mentioned jaw and cooperate with said connecting means to maintain gripping pressure on the cable in the event of failure of said resilient means.

35 10. A cable gripping mechanism for a cable carrier, comprising a frame, two jaws adapted to grip the cable and each having a pivot capable of limited movement with respect to said frame, resilient means acting upon one of said pivots so as to hold said jaws in cable gripping position, a hanger for the carrier, and means actuated by said hanger upon a breakdown of said resilient means for maintaining said jaws in cable gripping position.

40 45 11. A cable gripping mechanism for a cable carrier, comprising a frame, two jaws adapted to grip the cable and each having a pivot capable of limited movement with respect to said frame, resilient means acting upon one of said pivots so as to hold said jaws in cable gripping position, a hanger pivoted to said frame and urged by the load toward a normal position, and means actuated by said hanger upon a breakdown of said resilient means and acting upon the second pivot for maintaining said jaws in cable gripping position.

50 55 60 65 70 75 12. A cable gripping mechanism for a cable carrier comprising a frame, two gripping jaws pivoted in said frame on spaced-apart fulcrums and swingable from an open position to a closed position in which they can grip a cable, the fulcrums of both said jaws being displaceable in said frame for limited distances toward and away from an intermediate plane extending at right angles to the plane including said two fulcrums, resilient means urging one of said jaws with its fulcrum toward said intermediate plane, a hanger for the carrier pivoted to said frame and urged by the load toward a normal position, and means connecting said hanger to said second jaw so as to urge the fulcrum of the latter under the action of the load toward said intermediate plane and to move, in closed position of said jaws, said hanger away from its normal position

due to the displacement of the fulcrum of the second jaw away from said intermediate plane under the action of said resilient means through said first jaw upon said second jaw.

ALBERT FRIEDER
PAUL ZUBERBÜHLER.
